[57] ABSTRACT

A jacquard mechanism of otherwise conventional design, with a vertically reciprocating mounting board and a plurality of vertically extending hooks has the guide plate for the like plurality of harness cords fixedly connected to the mounting board. The harness cords connect respective hooks to operating pins carried by a bar.

3 Claims, 1 Drawing Figure

PATENTED APR 3 1973

JACQUARD MECHANISM

The present invention relates to jacquard mechanism with a vertically reciprocating mounting board, a plurality of vertically extending hooks extending upwardly from the board and having ends adjacent thereto, a like plurality of harness cords attached to the respective ends of the hooks and guided through corresponding holes in the board, a guide plate for the harness cords, and a bar carrying a like plurality of operating pins, each of the harness cords being attached to a respective one of the pins and the guide plate directing the respective cords to the pins associated therewith.

A conventional jacquard mechanism of the type which this invention is designed to improve is described and illustrated, for instance, in "Kettenwirkmaschine" (warp knitting machine) by E. Michael, Konradinverlag, Germany, Second Edition, 1952, pages 118-121. In such mechanism, the vertical hooks are usually lifted off the cooperating rails by a vertically reciprocating mounting board, the vertical hooks having spring-like bent ends adjacent the mounting board and adapted to rest in corresponding holes in the board. The resiliently tensioned harness cords are directly or indirectly attached to the ends of the hooks and are guided through the holes in the board. The mounting board is reciprocated by the machine drive. The harness cords are guided through the guide holes in a guide plate and are deflected towards the operating pins carried by a bar.

In this known mechanism, the harness cords are worn out rapidly as they pass through the respective guide holes, causing operating difficulties and frequent reassembly of the mechanism.

It is the primary object of the present invention to overcome these disadvantages by fixedly connecting the guide plate and the mounting board for common reciprocation.

Where a cord guide rail is interposed between the guide plate and the bar for deflecting the harness cords, additional friction is produced, which is reduced or eliminated according to a preferred embodiment of this invention by making the distance between the guide holes in the guide rail less than the distance between the operating pins.

It is also advantageous to avoid relative motion between the guide rail and the harness cords by fixedly connecting the guide rail with the guide plate.

The single FIGURE of the accompanying drawing illustrates, in a vertical section, a specific embodiment of the jacquard mechanism of the invention, only the essential parts of the otherwise conventional mechanism being shown.

The needles 3 extend transversely of the vertical hooks 4 of the jacquard mechanism and control movement of the hooks 4, the needles being controlled by an endless chain of suitably punched cards in a well known manner not shown herein. Each vertical hook 4 has an upper end 2 normally held by associated rail 1 and a

lower spring-like bent end 5 resting on holes in mounting board 7. The mounting board is vertically reciprocated in the direction of double-headed arrow 6, by the main drive of the machine. Connecting wire 8 is hooked at 9 to the harness cord 10 and to the bent end 5 of the vertical hook 4, the other end of the cord being attached to operating pin 11.

Vertically spaced from and below the mounting board is guide plate 12 whose guide holes 13 guide the cords. The guide plate is fixedly connected to the mounting board to form a unitary reciprocating assembly. In the illustrated embodiment, the connection is provided by bolts 14. In this manner, all relative motion between the guide plate, i.e., its guide holes, and the harness cords is avoided.

A cord guide rail 15 is interposed between the guide plate 12 and the bar 19 in which the operating pins 11 are resiliently mounted for vertical reciprocation. The distance 17 between the guide holes 16 in guide rail 15 is less than the distance 18 between the operating pins. This reduces the deflecting angle of the cords from the guide holes 13 in guide plate 12, thus reducing the friction between the cords 10 and the guide holes 16.

It is preferred to connect the guide rail fixedly to the guide plate, such connection being provided by bolts similar to those shown at 14, if desired. In this manner, there will be no relative motion at all between the guide rail and the cords.

I claim:

1. A jacquard mechanism comprising
  1. a vertically reciprocating mounting board,
  2. a plurality of vertically extending hooks extending upwardly from the board and having ends adjacent thereto,
  3. a like plurality of harness cords attached to the respective ends of the hooks and guided through corresponding holes in the board,
  4. a guide plate for the harness cords fixedly connected to the mounting board and vertically spaced from and below the board, and
  5. a bar carrying a like plurality of operating pins, each of the harness cords being attached to a respective one of the pins and the guide plate directing the respective cords to the pins associated therewith.
2. The jacquard mechanism of claim 1, further comprising a cord guide rail interposed between the guide plate for the harness cords and the bar carrying the operating pins, the guide rail having a like plurality of guide holes for respective ones of the cords, and the distance between the guide holes being less than the distance between the pins.
3. The jacquard mechanism of claim 1, further comprising a cord guide rail interposed between the guide plate for the harness cords and the bar carrying the operating pins, the guide rail having a like plurality of guide holes for respective ones of the cords and the guide rail being fixedly connected to the guide plate.
